US00D693856S

(12) **United States Design Patent**
Thompson et al.

(10) **Patent No.:** **US D693,856 S**
(45) **Date of Patent:** **** Nov. 19, 2013**

(54) **PRODUCT TANK LID FOR SEEDING AND PLANTING APPLICATIONS**

(71) Applicant: **CNH Canada, Ltd.**, Saskatoon (CA)

(72) Inventors: **Dennis G. Thompson**, Saskatoon (CA);
Jared S. Wright, Saskatoon (CA); **Jesse W. Gonzales**, Falls Church, VA (US)

(73) Assignee: **CNH Canada, Ltd.** (CA)

(**) Term: **14 Years**

(21) Appl. No.: **29/441,926**

(22) Filed: **Jan. 10, 2013**

(51) LOC (9) Cl. **15-03**

(52) U.S. Cl.

USPC **D15/28**

(57) **CLAIM**

The ornamental design for a product tank lid for seeding and planting applications, as shown and described.

DESCRIPTION

FIG. 1 is a top isometric view of a product tank lid for seeding and planting applications showing our new design;

FIG. 2 is a top plan view thereof;

FIG. 3 is a front elevational view thereof;

FIG. 4 is a side elevational view thereof;

FIG. 5 is a rear elevational view thereof;

FIG. 6 is a bottom plan view thereof; and,

FIG. 7 is a bottom isometric view thereof.

1 Claim, 5 Drawing Sheets
